The Steele & O'Leary

UNITED STATES PATENT OFFICE.

JOSEPH A. McAULEY, OF WEST NEW YORK, NEW JERSEY.

ATTACHING MEANS FOR REMOVABLE DENTURES.

1,297,199.

Specification of Letters Patent.

Patented Mar. 11, 1919.

Application filed March 4, 1918. Serial No. 220,386.

To all whom it may concern:

Be it known that I, JOSEPH A. McAULEY, a citizen of the United States of America, residing at 443 21st street, West New York, 5 N. J., have invented a new and useful Attaching Means for Removable Dentures, of which the following is a specification.

This invention has reference to removable dentures and the general objects of the invention are to provide simple, practical and 10 thoroughly satisfactory means for securing such dentures in place.

A special object of the invention is to provide a form of attaching means which will 15 hold the dentures securely in place and which at the same time will permit of the ready removal of the dentures.

In this connection it is the aim of my invention to provide a denture supporting or 20 attaching means which can readily be adjusted to compensate for wear and to meet particular requirements.

Briefly stated, the invention comprises a base member, which is usually stationary, as 25 by being secured fast to an abutment or the like, and an attaching member, which is usually carried by the denture and is constructed for engagement with the base member, said base member having an outstanding headed portion in the nature of a rail and the attaching member being of tubular 30 conformation to fit over said rail portion and having a flange or flanges to bear upon the base member. These flanges by their 35 frictional engagement with the base assist in holding the denture removably in place and furthermore provide a means by which the attaching member can readily be adjusted to fit it to the base.

Another feature of the invention is the 40 provision of a special form of stop for limiting the engaging movement of the co-operating members and which can readily be adjusted as required to meet different conditions.

A further feature is the slotting of the 45 tubular attaching member on opposite sides thereof to provide localized sections which may be "crimped" together to exert a binding force upon the base member when the two members are assembled.

Other features of the invention and the 50 details of construction will appear as the specification proceeds and will be made clear

from consideration of the accompanying 55 drawings which illustrates the invention embodied in practical commercial forms.

In said drawings—

Figure 1, is a broken perspective view 60 illustrating the invention as applied to the mounting of a denture in the form of a bridge.

Figs. 2 and 3 are detail perspective views 65 of the two co-operating members of the device.

Fig. 4 is a cross sectional view of said members in assembled relation.

Figs. 5 and 6 are detail perspective views 70 of the two co-operating members of a modified form of the device.

Fig. 7 is a plan view of said members in engaged relation.

Fig. 8 is a longitudinal sectional view of 75 the same substantially on the plane of line 8—8 of Fig. 7.

Fig. 9 is a cross sectional view thereof 80 substantially on the plane of line 9—9 of Fig. 8.

Fig. 10 is a view of the tubular sleeve member, looking at the open side thereof. 85

The base member of the device consists of a somewhat flattened base portion 5, which is usually slightly concaved at the back as indicated, to substantially fit the curvature of abutments or other elements such as those 85 indicated at 6 and 7 in Fig. 1, and an outstanding headed portion 8, in the nature of a rail, which is connected with the base by a narrowed or reduced neck portion 9. This supporting head 8 is preferably formed integrally with the base, the two being usually 90 rolled as an integral piece of stock which is subsequently cut to proper lengths to fit the work in hand.

The securing or attaching member is of 95 generally tubular construction as indicated at 10, shaped to fit the supporting head relatively closely and open along one side as indicated at 11 to permit of said member being slidably engaged longitudinally over 100 the supporting head with a telescopic movement. This longitudinal slot or opening 11, in the side of the tubular attaching member constitutes a throat receiving and closely fitting the neck 9 of the base member. Lat-

erally outstanding longitudinally extending 105 flanges 12 are shown provided at the opposite edges of the slot or opening in the side

of the tubular attaching member, said flanges in the illustration, frictionally engaging the face of the base at opposite sides of the supporting head. In addition to providing 5 this frictional engagement with the base member, these flanges reinforce the edge portions of the open-sided tubular attaching member and furthermore provide "grips" which may be readily engaged by a pair of 10 pliers or the like for the purpose of adjusting the attaching member to the base member. It has been found that these fittings wear more or less with use and this wear may be compensated for by simply pinching 15 together the opposite edges of the attaching member. These outstanding flanges provide a firm hold by which such edges may be gripped by a pair of pliers or the like, thereby facilitating the necessary adjustment and 20 enabling the parts being maintained in effective engagement at all times.

In the second form of my invention illustrated in Figs. 5 to 10 the tubular attaching member is shown as slotted longitudinally 25 at 13, on opposite sides thereof, just in rear of the outstanding flanges 12, to localize portions 14 at opposite edges of the throat in the side of the member, which can then be readily "crimped" or pinched together 30 more or less, as indicated at 15, to exert a certain "binding" tendency upon the base member. This construction enables the attaching member being adjusted to closely fit the base member intermediate its ends, while 35 fitting the base member relatively loosely at the opposite ends thereof. This allows of a certain "rocking" motion corresponding more or less to the movement of this character which the natural teeth have in functioning. As wear occurs it will be obvious 40 that these localized sections at the edges of the attaching member may be easily adjusted to bring about a proper engagement of the two members.

Under certain conditions it is desirable to 45 limit the engaging movement of the two members, for instance, in the case illustrated in Fig. 1, where it may be necessary to limit the movement of the denture toward the gum. In time however, the parts may recede, making it desirable to lower the denture farther toward the gum. The form of stop illustrated in Figs. 5, 7, 8 and 10 has 50 been designed to meet such conditions and 55 comprises a stop element 16 in the nature of a bar at the upper end of the attaching member connecting opposite edge portions of said attaching member, this stop bar fitting into the seat or recess 17 provided in the 60 top of the base member between the base and head portions thereof. The stop bar by its engagement with the bottom of this seat limits the movement of the denture toward the gum, but if it becomes necessary at any 65 time to lower the denture this may be easily

accomplished by cutting down the seat to the necessary extent. The seat is shown formed in the narrowest or neck portion of the base member, making the cutting down of the seat a simple matter. Another point 70 about the seating of the stop bar in a recess behind the head of the base member is, that this form of engagement has a tendency to cause the tubular attaching member to "hug" or be drawn more closely into engagement 75 with said head portion.

It will be apparent that the supporting post or base member may be made of elliptical, square, or angular shape in cross section instead of the circular form shown, the tubular attaching member in such case being made of corresponding shape so as to closely fit the same and it will be understood further that other changes may be made without departing from the true spirit and scope of 85 the invention. My invention contemplates that the post member instead of being made of solid metal as shown, may be stamped to shape from sheet metal. This is less expensive and has other advantages in that the 90 posts may be made more accurately to size and they possess a certain spring quality. A stamped sheet metal post further has the advantage that by reason of the fact that it is hollow, and an instrument may be inserted 95 therein to expand a portion thereof into frictional binding engagement with a particular portion of the tubular attaching member engaged thereon.

I claim:

1. Denture supporting means comprising, in combination, a headed supporting element and a tubular attaching element engageable thereover, said tubular attaching element being longitudinally slotted in opposite sides thereof and having portions adjacent the slots and separated by such slots from the body of the element crimped together to exert a binding effect upon the headed supporting element. 100

2. Supporting means for removable dentures comprising, a headed supporting member, a tubular attaching member open along one side thereof and slidably engaged over the headed supporting member, said tubular member having narrow and stiff lateral flanges at opposite edges of the open side thereof and being slotted longitudinally in rear of said flanges to separate said flanges for a part of their length from the body of 115 said member. 120

3. Supporting means for removable dentures comprising, a base and an outstanding headed supporting rail carried thereby, a tubular attaching member engageable over 125 the said headed rail, a stop on the end portion of the tubular attaching member for engagement with the supporting member, said supporting member having a recess therein located between the base portion and the en- 130

larged head portion thereof to receive said stop.

4. Attaching means for removable dentures comprising, a base plate and a headed rail carried thereby, said member having a seat therein between the base and rail portions thereof, a tubular attaching member open along one side thereof to slidably fit over the headed rail, outstanding lateral flanges at the opposite edges of said open side of the tubular attaching member, and a stop bar connecting the opposite edge portions of said open side engageable in the seat aforesaid, said tubular attaching member being longitudinally slotted in opposite sides thereof and having opposed edge portions at the open side thereof crimped together

to exert a binding effect upon the headed rail.

5. Supporting means for removable dentures comprising a base and an outstanding headed supporting rail carried thereby, a tubular attaching member engageable over said headed rail and open along one side thereof, and relatively narrow and stiff laterally outstanding flanges extending along the edges of said opening in the side of the tubular member to provide means by which the tubular member may be gripped for the purpose of adjusting said member and to reinforce said member for maintaining it in such adjusted condition.

JOSEPH A. McAULEY.
